Atty.

UNITED STATES PATENT OFFICE.

STANISLAW KOSINSKI, OF SCHENECTADY, NEW YORK, ASSIGNOR OF ONE-HALF TO
FRANK A. TABERSKI, OF SCHENECTADY, NEW YORK.

CUE-TIP.

1,349,069.

Specification of Letters Patent. Patented Aug. 10, 1920.

Application filed June 3, 1920. Serial No. 386,339.

To all whom it may concern:

Be it known that I, STANISLAW KOSINSKI, a citizen of the United States, residing at Schenectady, in the county of Schenectady, 5 State of New York, have invented certain new and useful Improvements in Cue-Tips, of which the following is a specification.

The present invention relates to cues such as are used in playing billiards and has for 10 its object to provide an improved arrangement for attaching the tips to the ends of the cue bodies.

For accurate and satisfactory use it is absolutely essential that the tip be firmly attached to the cue body and held against the end of the body so that the tip can never give nor work loose, and for this reason it is the common practice to glue the tips to the ends of the cues. However, the gluing 20 of tips to cues has certain well recognized disadvantages, and more particularly the object of my invention is to provide an improved arrangement for mechanically fastening a tip to the end of a cue whereby it is very firmly and tightly held and cannot work loose but at the same time it can be readily and quickly removed and replaced.

For a consideration of what I believe to be novel and my invention, attention is directed to the following description and the 30 claims appended thereto.

In the drawing, Figure 1 is a view partly in section of the small end of a cue embodying my tip fastening means; Fig. 2 is an 35 exploded view of the parts which go to make up the tip fastening means; Fig. 3 is an end view of one of the parts; Fig. 4 is a side elevation of a tip, and Fig. 5 is a view of a modification.

40 Referring to the drawing, (Figs. 1 to 4) 10 indicates the tapered wooden body of a cue which may be of any suitable structure and 11 indicates the tip which is applied to the small end of the body 10 and 45 is used in striking the ball.

Now, according to my invention, I provide an axially extending recess or hole 12 in the end of the cue body and in this hole is secured a rod or post 13 one end of which 50 projects beyond the end of the cue body to form a dowel 14. Rod 13 is preferably fastened in hole 12 by providing threads on the rod and screwing it into the hole and it may be further fastened by cementing it, the

cement being put in the threads when the 55 rod is being screwed into place. Rod or post 13 is made quite long so it threads well down into the end of the cue body, thereby providing a strong, metallic dowel 14 which is firmly anchored in the end of the cue body 60 and which cannot well break or come loose. In rod or post 13 is an axially extending threaded hole 15 which extends from the outer end of the rod or post 13 inwardly either partly or entirely through it. Or in 65 other words, dowel 14 is provided with an axially extending threaded hole. Dowel 14 has a smooth outer surface and fitting over it is one end of a sleeve 16 which may be made of ivory, celluloid or other suitable hard substances. The inner end of sleeve 16 is flat and fits against the end of the cue body and the sleeve is free to turn on dowel 14. The outer 70 end of sleeve 16 is dished or curved inwardly as indicated at 17, and is provided with projections forming axially extending cross-slots 18. Sleeve 16 may be made by taking a piece of material of suitable length with a small hole through it, counterboring the inner end and forming slots 18 in the outer end. The 80 cue tip 11 is made of strong leather such as elk's hide, for example, and is rounded outwardly on one side to fit the inwardly curved end 17 of sleeve 16. Fastened directly in the material of tip 11 is a metal ring 20 85 which presents an eye to receive a hook 21 on the outer end of a threaded pin 22. Ring 20 may be fastened in tip 11 by first making a curved hole in the tip by means of a suitable tool, threading a piece of curved metal 90 wire through it, and then bringing the ends of the wire together and soldering them. With this arrangement I have found that the ring is firmly held in the tip and that 95 it will withstand a very considerable pull without tearing out. The portion of ring 20 which projects beyond tip 11 to form the eye extends at substantially a right angle to hook 21 which engages therewith and such eye and hook are located in slots 18 in 100 the end of sleeve 16, the pin 22 which carries hook 21 being threaded into hole 15 in dowel 14.

In fastening a tip to the cue body hook 21 is hooked into the eye formed by ring 20 105 and pin 22 is passed through sleeve 16 to bring the surface of the tip against the end of the sleeve and the hook and eye into slots

18. Pin 22 is then threaded into hole 15, this being done by turning sleeve 16. Pin 22 is preferably made sufficiently long to extend entirely through the sleeve 16 so it may be 5 easily started into hole 15 and the threads on it are of a fine pitch so the tip can be very firmly drawn down onto the end of the sleeve and be less likely to work loose. As will be clear, when sleeve 16 is turned tip 10 11 and pin 22 turn with it due to the eye and hook engaging in slots 18 and as the sleeve is turned the pin threading down into hole 15 will pull the tip into very firm engagement with the end of the sleeve, the outwardly 15 curved side of the tip being pulled down into the dished end 17 of the sleeve. When firmly 20 screwed down sleeve 16 is held tightly between tip 11 and the end of cue body 10, and acts in substance as a lock nut to prevent the tip from working loose.

In connection with the foregoing arrangement it is to be particularly noted that in fastening the tip in place I do not screw the tip itself but screw a sleeve made of solid 25 material thereby pulling the tip down into place. I have found that if an attempt is made to screw a tip, the tip gives or yields and a firm anchoring of the tip is not possible. By screwing a sleeve, however, and 30 pulling the tip down onto it an absolutely tight engagement can be obtained. It will also be clear that a tip can be quickly and easily removed and a new one substituted for it.

35 In Fig. 5 I have shown a modified arrangement of dowel on the end of the body member of the cue. In this arrangement the dowel 25 is formed as an integral part of a sleeve 26 which sleeve is fastened to the 40 end of the body of the cue in a suitable manner as by fastening it on a projection 27. Dowel 25 and sleeve 26 may be formed of a suitable hard substance such as metal, ivory, celluloid or the like, and the dowel is provided with an axially extending threaded hole 28 which may be formed directly in the material of dowel 25 or in a suitable inset 29 located in a hole in dowel 25, as shown, the arrangement depending upon the 45 material used. Otherwise the arrangement shown in Fig. 5 is substantially the same as that of Figs. 1 to 4, and similar reference numerals have been applied to corresponding parts.

50 In accordance with the provisions of the patent statutes, I have described the principle of operation of my invention, together with the apparatus which I now consider to represent the best embodiment thereof, but 55 I desire to have it understood that the apparatus shown is only illustrative, and that the invention may be carried out by other means.

What I claim as new and desire to secure by Letters Patent of the United States is:—

1. In a cue, the combination of a cue body having a dowel at one end provided with an axial threaded opening, a sleeve on the dowel, a tip, means forming an eye on the tip, a pin which extends through said sleeve and has a hook on one end engaging with said eye, the other end of said pin being threaded into said opening, and connecting means between the pin and sleeve which prevents the pin from turning relatively to the sleeve, but permits it to move axially thereof.

2. In a cue, a cue body having an axially extending opening at the tip end, a rod fastened in said opening and projecting beyond the end of the cue body to form a dowel, there being an axially extending threaded hole through said dowel, a tip, a pin fastened at one end to said tip, the other end being threaded into said hole, a sleeve on said dowel between the tip and the end of the cue body, and engaging means between the pin and sleeve which causes the pin to turn with the sleeve and permits it to move axially thereof.

3. In a cue, a cue body having an axially extending opening in one end, a tip, an eye connected to the tip, a pin having a hook at one end which engages said eye, the other end being threaded into said opening, and a sleeve located between the tip and the end of the cue body, said sleeve having a slot in which said eye is located.

4. In a cue, a cue body having an axially extending opening in one end, a tip, an eye connected to the tip, a pin having a hook at one end which engages said eye, the other end being threaded into said opening, and a sleeve located between the tip and the end of the cue body, said sleeve having cross-slots in which said eye and hook are located.

5. In a cue, means for fastening the tip to the end of the cue body comprising a rod fastened to the end of the body and provided with an axially extending threaded hole, a sleeve on the end of said rod against which the tip rests, a ring partially embedded in said tip to form an eye, a pin having a hook on one end which engages said eye, the other end of said pin threading into said hole, and means connecting the eye and hook to the sleeve which prevents them from turning in it but permits them to move axially thereof whereby when the sleeve is turned in one direction the pin will be screwed into said hole to draw the tip against the end of the sleeve.

6. In a cue, a wooden cue body having a hole at its smaller end, a short rod fastened in said hole and projecting beyond the end

of the body to form a dowel there being an axially extending threaded hole through said dowel, a sleeve the inner end of which fits over said dowel and is adapted to turn 5 thereon, the outer end of said sleeve being provided with a slot, a tip which rests on the outer end of said sleeve, a ring fastened to said tip to form an eye, said eye resting in said slot, and a pin which extends through said sleeve and has a hook at one end which engages said eye, the other end being threaded into said hole in the dowel. 10

In witness whereof, I have hereunto set my hand this 26th day of May, 1920.

STANISLAW KOSINSKI.
